(57) **CLAIM**

The ornamental design for a motivational device, as shown and described.

DESCRIPTION

FIG. 1 is a front-right upper perspective view of a motivational device showing the new design;

FIG. 2 is rear-left bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is front-right upper perspective view of the motivational device showing the new design in an alternative environment;

FIG. 10 is rear-left bottom perspective view thereof;

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.

The broken line showing of the drawings illustrate portions of the motivational device that do not form a part of the claimed design.
